United States Patent [19]

Cattaneo

[11] Patent Number: Des. 401,171

[45] Date of Patent: **Nov. 17, 1998

[54] ELECTRICAL CURRENT SENSOR

[75] Inventor: **Pierre Cattaneo**, Collonges s/Saleve, France

[73] Assignee: **Liaisons Electroniques-Mecaniques LEM S.A.**, Plans-Les-Ouates, Switzerland

[**] Term: **14 Years**

[21] Appl. No.: **78,667**

[22] Filed: **Oct. 29, 1997**

[30] Foreign Application Priority Data

Jun. 12, 1997 [XH] Hague Agreement DM/040464

[51] LOC (6) Cl. **10-04**

[52] U.S. Cl. **D10/78; D10/75**

CLAIM

The ornamental design for an electrical current sensor, as shown.

DESCRIPTION

FIG. 1 is a front elevational view of the electrical current sensor, showing my new design;

FIG. 2 is a bottom view of the electrical current sensor;

FIG. 3 is a top view of the electrical current sensor;

FIG. 4 is a left view of the electrical current sensor;

FIG. 5 is a right view of the electrical current sensor; and,

FIG. 6 is a rear elevational view of the electrical current sensor.
